(57) **CLAIM**

The ornamental design for a display screen portion with animated graphical user interface, as shown and described.

DESCRIPTION

FIG. 1 is a front view of a display screen portion with animated graphical user interface showing our new design; and, FIG. 2 is a second image thereof.

The appearance of the transitional image sequentially transitions between the images shown in FIGS. 1 and 2.

The broken lines shown in the figures of a display screen and portions of the graphical user interface, including the text, numbers and symbols are for the purpose of illustrating portions of the article, and form no part of the claimed design.
